his Attorney.

UNITED STATES PATENT OFFICE

ERIK LANGE, OF STARNBERG, GERMANY, ASSIGNOR TO FIRM LANGE & CO., GESELLSCHAFT MIT BESCHRANKTER HAFTUNG, OF STARNBERG, GERMANY

FLAG TRUCK

Application filed July 29, 1930, Serial No. 471,568, and in Germany June 30, 1930.

The invention relates to a flag-truck, consisting of ceramic material (porcelain) and containing inside its headpiece channels through which the flag-line is pulled and inside its neck or staff hollows to admit fitting-screws. The truck is glazed and gilt at least on the part of the surface exposed to the weather. The channel for the flag-line may be laid in its entire length inside the truck, so that it disembogues to the outside only with its two shanks at the under-side of the truck or neck-piece. A hollow for fitting a lightning-conductor may be provided in the crown of the head-piece.

15 The attached drawings show some methods of construction of the object of the invention, viz.

Figure 1, a method of construction in axial section.

20 Figure 2, an oblique section to Fig. 1.

Figure 3, a second method of construction in axial section on line A—B to Fig. 4.

Figure 4, a horizontal section to Fig. 3.

Figure 5, a side view to Fig. 3.

25 Figure 6, a third method of construction in axial section.

Figure 7, a section on line C—D to Fig. 8.

Figure 8, a fourth method of construction in horizontal section.

30 As per Figs. 1 and 2 the flag-truck according to this invention consists of a head-piece *a* and a hollow adjoined piece *b* of the neck; both parts are made in one piece, that is of ceramic material like porcelain, earth-

35 enware or the like. The part of the truck exposed to the weather is glazed and gilt. To lessen its weight, the head-piece *a* is supplied with a ring-shaped cavity *c*; it further has two parallel axial channels *d* and *e* (Fig. 2) through which the flag-line is pulled. The adjoined piece *b* of the neck has radial hollows *g* to admit the screws *i*, joining truck and flag-pole *h*. The hollows *g* are covered by the head-piece *a*, so that no mois-

40 ture can enter.

The method of construction of the Figures 3—5 differs from the one just described inasmuch as two pairs of parallel axial channels *k*¹ and *k*² and *l*¹ and *l*² are provided for pulling two flag-lines through, as well as a 50 hollow *m* in the crown to insert a lightning-conductor. Further the neck is stronger and longer and supplied with two bored holes *g* sitting transverse opposite each other for fitting-screws.

According to Fig. 6 the channel *n* for pulling the flag-line through runs in its full length inside the flag-truck, viz. partly inside the head *a*, partly in the adjoined piece *b* of the neck, so that the two shanks *n*¹ and *n*² of the hollow disembogue to the outside solely at the under-side. The advantage of this arrangement as compared with that of Fig. 2 consists in the fact that with the latter moisture may enter the channels *d* and *e* 60 which disembogue to the outside also on the upper-side, a disadvantage avoided according to Fig. 6. The hollow of the neck is 65 conical in this instance instead of being cylindrical.

A similar method of construction is shown by Figs. 7 and 8, but with the deviation, that in this instance the channel *o* for the flag-line is entirely inside the head-piece *a*, so that the adjoined piece *b* of the neck may be 70 made thinner.

The advantage of the flag-truck according to this invention as compared with known methods of construction of this kind lies in the fact that it is of comparatively 80 little weight and is not exposed to destructions by influence of the weather and further affords a secure protection of the flag-pole against moisture and destruction. It does not need any special devices which 85 often cause trouble like rolls to guide the flag-line; the friction of the line against the porcelain is so small that it is practically negligible.

What I claim is:

55

60

65

70

75

80

85

90

1. A hemispherical hollow head piece of ceramic material for a flag staff having orifices to accommodate the flag rope, and a depending collar the lower end of which extends below the plane of the center of the arc described by the hemispherical surface of the head.
  2. A hollow head piece as claimed in claim 1, including a guide groove in the surface of the head projecting from one orifice to the other.
  3. A hollow head piece as claimed in claim 1, including a set screw adjustable in the collar to attach the head piece to the staff.
- 15 In testimony whereof I hereunto affix my signature.

ERIK LANGE.
